UNITED STATES PATENT OFFICE.

JOHN FORSTROM, OF CHICAGO, ILLINOIS.

ENGINE.

1,254,219.

Specification of Letters Patent. Patented Jan. 22, 1918.

Application filed April 22, 1916. Serial No. 92,853.

To all whom it may concern:

Be it known that I, JOHN FORSTROM, a citizen of the United States of America, and a resident of Chicago, county of Cook, 5 and State of Illinois, have invented certain new and useful Improvements in Engines, of which the following is a specification.

This invention relates to engines having pistons which reciprocate relatively of the 10 engine cylinders, but wherein such relative reciprocation is accomplished by causing the cylinders to rotate around a center, which is eccentric to a center around which the support for the pistons is rotated.

15 The main object of this invention is to provide an improved valve for insuring the desired supply of fluid to and the exhaust from engine cylinders at the required times.

An illustrative embodiment of this invention is shown in the accompanying drawing, 20 in which:

Figure 1 shows an end view of an engine constructed according to this invention.

Fig. 2 represents a longitudinal section 25 taken on the line A—A of Fig. 1.

Fig. 3 is an enlarged perspective view of the valves for controlling the engine.

Fig. 4 is a side elevation of the valve structure shown in Fig. 3.

30 Fig. 5 is a sectional detail taken on the line B—B of Fig. 4.

Fig. 6 is a sectional detail taken on the line C—C of Fig. 4.

Fig. 7 is an end view of the valve structure shown in Fig. 4.

Fig. 8 is a fragmentary detail showing a means for supporting the engine cylinders.

The purpose of this invention in general is to combine in one machine mechanical 40 structures having some of the advantages of rotary engines, and some of the advantages of the ordinary reciprocating type of engine, while at the same time avoiding certain losses in efficiency occurring in both 45 of said types of engines. An example is, the loss of power usually occurring in rotary engines, due to the fact that the expansive power of the operating fluid is utilized to only a limited extent. Also, in reciprocating 50 engines, more or less power is lost in overcoming the inertia of the piston at the end of its stroke, and the engine is correspondingly strained and racked, due to its vibration during the reversal of the movement of the piston, whereas in the present 55 engine, the pistons and cylinders reciprocate

relatively of each other, while continuously rotating about different eccentrically arranged centers and, therefore, making it unnecessary to overcome the inertia of heavy 60 moving parts but enabling such inertia to be utilized, as in a fly wheel in continuing the action of the engine.

In the drawings, a spoked wheel structure 1 is shown keyed to a driven shaft 2, the 65 bearings for which are omitted from the drawings. A plurality of piston rods 3 are pivoted by pins 4 to lugs 5 on the inner side of the flange 6 of wheel 1. At their inner ends, the rods 3 are provided with 70 piston heads 7 fitted within cylinders 8 which are in turn rotatably mounted on the fixed shaft 9 which is supported on one end by a fixed member 10, into which it is driven, and at its opposite end by a member 75 11 in which the inner end of shaft 2 is journaled. The member 10 serves to support the end of shaft 9 by bearing on shaft 2, which in turn is supported by separate bearings. At their inner ends, the cylinders 8 80 are each provided with curved bearing flanges 12 which engage the hollow shaft 13, between which and the shaft 9 are preferably located roller bearings 14. The bearing flanges 12 are held in contact with shaft 85 13 and radial displacement of the cylinders is prevented by U bolts 16.1 passing around the hollow shaft 13, and through the flange 16 of the cylinders 8. The bolts 16.1 may be tightened as desired by nuts 16.2 threaded to 90 the ends thereof. Displacement of the cylinders longitudinally of shaft 9 is prevented by bearing member 10 and the member 11.

Rigid with the bearing member 10 and shaft 9 is a conical valve 15, the conical 95 surface of which bears against a rotating block 17 having a correspondingly conical recess 17.1. The block 17 is connected by bolts 18 passing between the cylinders 8 to a plate or disk 19 rigid with sleeve 13 and 100 bearing against the plain surface 20 of one side of the cylinders. The inner face 21 of block 17 bears against the plane faces 22 on the opposite side of the cylinders.

The above described mounting of the engine cylinders, while preventing their radial or lateral displacement, permits a slight independent angular motion of the cylinders around the shaft, by which motion the cylinders and pistons remain in true alinement 110 as they respectively rotate around eccentric centers.

Each cylinder 8 is provided with passages 23 and 24 in the end wall 25 and the side wall 26, these passages respectively communicating with the interior of the cylinder 5 near its inner and outer ends. The passages 23 and 24 alternately serve as intake and exhaust passages. Thus, while the cylinder is exhausting through the passage 23, steam will be admitted thereto at the 10 opposite side of the piston through the passage 24 and when the cylinder is exhausting through the passage 24, steam will be admitted through the passage 23. The passages 23 and 24 of each cylinder respectively 15 communicate with passages 27 and 28 in the block 17. This block rotates with the engine and for this purpose is preferably provided with lugs 29 extending between the cylinders, and which are engaged by 20 corresponding lugs 29.1 on the cylinders. The passages 27 and 28 are somewhat elongated as shown in Fig. 3, at the points where they communicate with the passages 23 and 24, to insure proper communication 25 therewith irrespective of the slight relative angular motion of the cylinders with respect to block 17. Packing 30 may be provided between the faces 21 and 22 of the cylinders and block 17 to prevent leakage 30 of steam between the passages 27 and 28 or 23 and 24, although said faces are held in fairly firm contact by bolts 18.

During rotation of the engine the passages 27 and 28 communicate by ports 31 35 and 32 with different ones of grooves 33 to 40 inclusive, cut in an annular direction in the conical face 41 of the valve member 15. These grooves may constitute supply and 40 exhaust passages, according to their connection with the steam supply inlet 42 or the exhaust outlet 43 in member 10 as controlled by throttle valve 44. The throttle valve has a passage 45 extending diametrically therethrough and having an enlarged 45 opening 62 in communication with the inlet port 32, and it also has exhaust passages 46 communicating, through the space 46.1 at the rear of valve 44, with the exhaust port 43 in member 10. The grooves 33 and 34 50 respectively communicate with passages 47 and 48 leading to the conical recess 49 within which the throttle valve 44 is fitted. Also, the grooves 37 and 38 communicate 55 respectively through passages 50 and 51 with the recess 49.

The valve member 15 is also provided with passages 52 to 55 inclusive, which provide communication respectively between the grooves 33 and 39, 34 and 40, 35 and 37, 60 36 and 38. When the throttle valve 44 is in the position shown in Fig. 4, the outlet port 56 of the steam supply passage 45 does not register with any of the ports 57 to 60 inclusive, of the passages 47, 48, 50, and 51, 65 Fig. 4, and, therefore, no motive fluid is

supplied to any of the cylinders of the engine, but when the valve 44 is turned approximately 45° to the right or left by manipulation of the handle 61 tapped into the stem 44.1 of the throttle valve, the port 56 70 comes into alignment with one or both of ports 57 and 58, or 59 and 60. The inlet port 62 of supply passage 45 is very much elongated as shown in Fig. 4, in order that it shall remain in communication with the 75 supply passage 42 in any of the positions to which the throttle valve may be set.

If the throttle valve is moved to the position in which port 56 registers with port 57, steam enters passage 47 from which it 80 is delivered to the groove 33 in the conical valve member 41. Steam is at the same time delivered to groove 39 in the said valve member, through the passage 52, which connects the last mentioned groove with the 85 groove 33. Steam will, therefore, be delivered to two of the engine cylinders through the passages 27 and 24 for one cylinder, and 28 and 23 for another cylinder. The steam which enters passage 27 from the groove 90 33 through the inlet port 32 passes to one of the engine cylinders through the passage 24 therein, the steam being delivered to the outer end of the cylinder in back of a piston 7. The steam which is delivered from 95 groove 39 to the passage 28 in block 17 enters another cylinder through the passage 23 in the inner end thereof, in front of its respective piston. The action of the steam tends to force one piston inwardly and the 100 other piston outwardly with respect to their respective cylinders, the force of the expansion ultimately acting between the pivotal point 4 of the pistons and the stationary crank shaft 9 which is eccentric to the center of rotation of wheel 1. The wheel is thereby caused to rotate as if under the influence of an expanding and contracting pitman, pivoted at one end to the rim of the wheel and at its opposite end to some stationary support. As the ports 32 and 31 105 respectively pass beyond the grooves 33 and 39 from which they are receiving a supply of steam and come into communication with the grooves 34 and 40, the supply of steam is 110 shut off since the said grooves are not in communication with the supply conduit 45. As this particular pair of ports 32 and 31, which had been receiving steam, pass over the grooves 34 and 40 the steam continues 115 to expand in the particular cylinders to which it had been admitted, causing the pistons thereof to move relatively in said cylinders in opposite directions. Continued 120 rotation of the engine causes the same ports to pass over the grooves 37, 38, and 35, 36, which are connected in pairs by the passages 125 54 and 55, as above mentioned, permitting the steam to exhaust to one of the exhaust passages 46, through said grooves and pas- 130

sages 50 and 51, upon the reversal of the pistons. The operation is repeated for each cylinder as its respective ports 31 and 32 pass over the grooves in the valve member 15 in the successive order above mentioned.

The operation of the engine is accomplished by permitting steam to enter through the port 57 of passage 47, or the port 59 of passage 50, Fig. 4. For this purpose, throttle valve 45 is angularly adjusted by means of handle 61 to bring the feed port 56 opposite either the ports 57 or 59. By such adjustment of the throttle, the engine may be caused to rotate in a forward or a reverse direction. For instance, if the port 56 is caused to register with the port 57, port 58 will be closed by the solid surface of throttle valve 45 and the ports 59 and 60 will register with an aperture 46 in the 20 throttle valve, which serves as an exhaust conduit by being in communication with the exhaust port 48 as shown in Fig. 4. Steam entering the port 57 is delivered to groove 33, and from said groove through passage 25 52 is delivered to the groove 39. The pair of cylinders which communicate at such time with the grooves 33 and 39 by the ports 31 and 32, accordingly receive steam at opposite sides of their respective pistons, causing the engine to rotate in the direction in which the force is applied between the pistons and the stationary crank shaft 9. The steam is shut off as the particular pair of ports 31 and 32 pass over grooves 34 and 35 40, and is exhausted as these ports pass over grooves 37, 38, and 35, 36.

If the throttle valve 45 is adjusted to cause the steam supply port 56 to register with the port 59, steam is admitted to the grooves 40 38 and 36, which now become feed ports, while the grooves 37 and 35 are closed to the engine cylinders and also to the exhaust, since a solid part of the throttle valve covers port 60. The steam in the 45 cylinders is thereby permitted to expand during the passage of a pair of ports 31 and 32 over the said last mentioned grooves. When these same ports register with the grooves 34, 33, and 40, 39, the respective 50 cylinders exhaust.

It is possible to so adjust the throttle valve that the port 56 thereof will register

more or less with a pair of ports 57, 58, or 59, 60. In such case, the grooves of the valve 15, which ordinarily are dead during the expansion of the steam in the cylinders, become feed grooves and the steam is delivered at full pressure during the entire stroke of the piston.

Although but one specific embodiment of this invention has been herein shown and described, it will be understood that numerous details of the construction shown may be altered or omitted without departing from the spirit of this invention as defined by the following claims.

I claim:

1. An engine, comprising a driven rotatable member, a plurality of pistons radially mounted on said member, a plurality of 70 cylinders coöperating with said pistons, said cylinders being mounted to rotate around a support therefor which is eccentric to the support for said driven rotatable member, and a valve structure arranged to supply an 75 operating fluid to said cylinders during their rotation, said valve structure being provided with two sets of four annularly alined grooves, passages connecting the opposite grooves of opposite sets, and adjustable 80 means for supplying steam to any pair of communicating grooves and providing an outlet from two pairs of the remaining grooves.

2. An engine, comprising a driven rotatable member, a plurality of pistons radially mounted on said member, a plurality of cylinders coöperating with said pistons, said cylinders being mounted to rotate around a support therefor which is eccentric to the support for said driven rotatable member, and a valve structure arranged to supply an 90 operating fluid alternately into opposite ends of said cylinders during their rotation, said valve structure being provided with two 95 sets of four annularly alined grooves, passages connecting the opposite grooves of opposite sets, and adjustable means for supplying steam to any pair of communicating 100 grooves and providing an outlet from two pairs of the remaining grooves.

Signed at Chicago this 18th day of April, 1916.

JOHN FORSTROM.
